UNITED STATES PATENT OFFICE

155,722

DESIGN FOR A PENDANT ORNAMENTAL FRAME FOR COSTUME JEWELRY

Anthony J. Mascia, Flushing, N. Y.

Application March 5, 1949, Serial No. 1,252

Term of patent 3½ years

(Cl. D45—17)

To all whom it may concern:

Be it known that I, Anthony J. Mascia, a citizen of the United States, residing at Flushing, in the county of Queens, in the State of New York, have invented a new, original, and ornamental Design for a Pendant Ornamental Frame for Costume Jewelry, of which the following is a specification, reference being had to the accompanying drawing, forming a part thereof.

Fig. 1 is a front elevational view of a pendant ornamental frame for costume jewelry, showing my design; Fig. 2 is a side elevational view of the same.

I claim:

The ornamental design for a pendant ornamental frame for costume jewelry, as shown.
ANTHONY J. MASCIA.
